UNITED STATES PATENT OFFICE.

FRANK E. MAYOL, OF SALT LAKE CITY, UTAH.

DESIGN FOR A CONTAINER FOR FROZEN DAINTIES.

Application filed June 19, 1922. Serial No. 2,744. Term of patent 3½ years.

To all whom it may concern:

Be it known that I, FRANK E. MAYOL, a citizen of the United States, residing at Salt Lake City, in the county of Salt Lake and State of Utah, have invented a new, original, and ornamental Design for a Container for Frozen Dainties, of which the following is a specification, reference being had to the accompanying drawing, forming part thereof.

The figure is a perspective view of the container for frozen dainties, showing my new design.

I claim:

The ornamental design for a container for frozen dainties, as shown.

FRANK E. MAYOL.
